(57) **CLAIM**

The ornamental design for a bottle, as shown and described.

DESCRIPTION

FIG. 1 is a top, side perspective view of the present invention;
 FIG. 2 is a side elevational view thereof;
 FIG. 3 is a top plan view thereof; and,
 FIG. 4 is a bottom plan view thereof.

The broken lines in the drawings are included for the purpose of illustrating environment and form no part of the claimed design.
